UNITED STATES PATENT OFFICE.

WALTER SAVAGE, OF CROOKSTON, MINNESOTA.

SNOW-PLOW.

SPECIFICATION forming part of Letters Patent No. 234,814, dated November 23, 1880.

Application filed September 29, 1880. (No model.)

To all whom it may concern:

Be it known that I, WALTER SAVAGE, of Crookston, in the county of Polk and State of Minnesota, have invented a new and Improved 5 Snow-Plow, of which the following is a specification.

The object of this invention is to provide an improved snow-plow for removing snow from railroad-tracks.

10 Figure 1 is a plan of the plow. Fig. 2 is a sectional side elevation of the same on line x x , Fig. 1. Fig. 3 is a transverse sectional elevation on line y y , Figs. 1 and 2. Fig. 4 is a transverse sectional elevation on line z z , Fig. 15 2. Fig. 5 is a partial plan of the reverse of the plow.

Similar letters of reference indicate corresponding parts.

In the drawings, A represents the body of 20 the plow; B, the flat share or top thereof, having a broad beveled point, a , and extending rearward the full length of the body A, with an upward slope of fifteen degrees, or thereabout, and overhanging the body A, on both 25 sides thereof.

C C are the wheels, preferably eight in number, set beneath the body A of the plow to be better protected from the snow.

D is a dividing-block or mold-board, some- 30 what of a diamond shape, fixed rigidly and centrally on the higher part of the top B, with its sharper end forward. Below the block or mold-board D triangular wings E E are hinged

to the sides of the share or top B, so that when not in use they hang perpendicularly, and when in use will be elevated by pressure of the snow beneath them on a level with the face of the top B, and serve to guide or throw the snow clear of the track. Behind the rear and broader ends of these wings E E the body, 35 top or share, and block or mold-board A B D, respectively, are made wedge-shaped, as shown at b , that the plow may offer a minimum of resistance in the snow to the backing up of the locomotive to which it may be attached. 40

This plow is designed to be made of wood clad with iron to increase its weight, strength, and durability.

Having thus described my invention, I claim as new and desire to secure by Letters Patent—

1. An improved snow-plow constructed substantially as herein shown and described, consisting of body A, flat, sloping, overhanging top or share B, wheels C C, dividing-block or 55 mold-board D, and hinged triangular wings E E, said plow having its rear wedge-shaped, as set forth.

2. In a snow-plow, the combination, with the top or share B, of the hinged triangular 60 wings E E, substantially as herein shown, and for the purpose described.

WALTER SAVAGE.
